UNITED STATES PATENT OFFICE.

BERTRAM J. GOLDSMITH AND EMIL KOEB, OF NEW YORK, N. Y., ASSIGNEES, BY MESNE ASSIGNMENTS, TO PERFECT WINDOW REGULATOR CORPORATION, OF LONG ISLAND CITY, NEW YORK, A CORPORATION OF DELAWARE.

WINDOW AND DOOR CONSTRUCTION.

Application filed August 28, 1924. Serial No. 734,583.

Our invention relates to window and door construction in which a window is slidable vertically in a suitable frame, the invention being particularly adapted in its application to vehicle doors carrying a window of the type specified.

The principal object of the invention is the production of a simple and unitary device which shall contain all the necessary mechanism for raising and lowering the window as well as means for holding the door closed, which device may be shipped and installed as a unit.

A further object of the invention is the production of a device of the character specified which shall be so constructed as to permit the crank or handle for actuating the window to take a position where it will not be apt to interfere with the operator or others.

Other and further objects and advantages will appear from the accompanying description, the invention consisting in the novel device and parts thereof hereinafter more particularly described and then specified in the claims.

In the accompanying drawing showing a practical embodiment of the invention:

Fig. 1 is a front elevation of a portion of a vehicle door showing the invention as applied thereto.

Fig. 2 is a horizontal section taken through the door.

Referring in detail to the several figures of the drawing:

1 indicates the side members of a frame of a door which are provided with guideways 2 in which a window or sash 3 is vertically slidable. Fastened to the lower edge of the window is a U-shaped channel strip 4. Extending horizontally across the frame and fastened to both of the side members by suitable screws as shown, or otherwise, is a metallic plate or lock-board 5 provided with a horizontal flange 6 at the upper edge thereof which may be fastened to the window sill (not shown). Said plate 5 may constitute a portion of the front wall of the window well into which the window is slidable, the rear wall being indicated at 7. The said plate is also provided with a vertical flange 8' engaging the side of the right-hand side member 1.

8 indicates an annular recess or depression

pressed inwardly from the plate 5. Mounted in the depression preferably centrally thereof is an escutcheon or bearing 9 carrying the hub or shaft of a crank or handle 10. The inner end of said hub has mounted thereon a pinion 11 meshing with a toothed segment 12 forming a part of or securely attached to a pivoted operating arm 13 which is pivoted to the inner side of the plate 5 at the place of the depression 8. Said arm 13 is provided with a roller 14 at the outer end thereof engaging within the channel 4. Springs 15 are also provided, the inner ends of which are secured to a hook 16 fastened to the inner wall of the depression 8 or pressed out of the metal thereof, the outer ends of said springs being fastened to the outer end of the arm 13. Said springs exert an upward effort on the arm 13 and consequently assist in raising the window. To raise or lower the window the crank or handle 10 is rotated, motion being transmitted through pinion 11, toothed segment 12, operating arm 13 and roller 14 which rides in the channel 4. The mounting of the escutcheon 9 and handle 10 in the depression 8 outwardly of the general plane of the plate 5 is desirable as it prevents these parts from interfering with the operator or catching on the clothes of persons and also places the pivotal support for the arm 13 closely adjacent to the plane of the window 3.

On the right-hand side of the plate 5 we mount a handle 17 the shank of which is indicated at 18 and which is pivoted to said plate as indicated. Secured to the lower end of the shank is a latch bolt actuator 19 adapted to extend through a slot in the righthand side member 1 and through a slot in the flange 8', into a keeper housing 20 formed by cutting out a portion of the right-hand side member 1. Secured to the plate 5 and to the latch bolt actuator is a spring 21 which normally acts to retain said latch bolt actuator in retracted position. The plate 5 may also be provided with lugs 22 punched out of the metal of the plate and adapted to engage the shank 18 to limit the movement of the handle 17.

23 indicates a wall adjacent the door frame which is provided with a housing 24 to the rear wall of which a spring 25 is secured, said spring also being fastened to a latch bolt 26 which normally projects, by the action of

said spring, into the keeper housing 20 thereby retaining the door in closed position. To 5 retract the latch bolt within its housing whereby the door may be opened, the handle 17 is actuated against the action of the spring 21, whereby the latch bolt will be forced back into its housing against the action of the spring 25 by the member 19. As soon as the handle 17 is released, however, the spring 21 10 forces it back into first position and the latch bolt is then projected outwardly by the action of its spring 25.

After the device has been installed the forward portion of the door may be covered by 15 any suitable cover or upholstery which is indicated at 27.

What we claim as our invention is:—

1. In a device of the character described, a frame provided with side members, a window 20 25 slidable therein, a metallic plate secured to one of said side members and provided with a projecting portion removed from the plane thereof, mechanism for raising and lowering said window positioned upon the outer face 25 of said projecting portion and a handle mounted in said depression and associated with said mechanism for actuating the same.

2. In a device of the character described, a frame provided with side members, a window 30 35 slidable therein, a metallic plate secured to one of said side members and provided with a depressed portion integral therewith, an operating arm engaging the window and pivoted to a wall of said depression, a handle mounted in said depression and means connecting said handle and said operating arm.

3. In a device of the character described, a frame provided with side members, a window slidable therein, a plate secured to one

of said side members and provided with a 40 depression therein, an operating arm engaging the window and pivoted to a wall of said depression, an escutcheon mounted in said depression, a rotatable handle mounted therein, means connecting said handle and said 45 operating arm and a spring urging said arm upwardly on its pivot and secured to the depressed portion of said plate.

4. In a device of the character described, a frame provided with side members, a window slidable therein, a metallic plate secured 50 to said side members and provided with a depression therein pressed out of the metal thereof, an operating arm pivoted to said plate and engaging the window, a handle mounted in said depression, means connecting said handle and operating arm, a hook carried by the depressed portion of said plate and a spring fastened to said hook and said 55 arm and urging said arm upwardly.

5. In a device of the character described, a frame provided with two side members, a window slidable in said side members, a metallic plate extending across the frame and attached to said side members and being 60 formed so as to engage two surfaces of one of said side members, said metallic plate being provided with a depression therein, means mounted on said plate for raising and lowering the window and an actuating 70 handle mounted, within said depression and connected to said means.

Signed at New York in the county of New York and State of New York this 27th day of August, A. D. 1924.
